Primary Examiner — Elizabeth J Oswecki(74) *Attorney, Agent, or Firm* — Boyle Fredrickson, S.C.(57) **CLAIM**

The ornamental design for a disposable face shield, as shown and described.

DESCRIPTION

FIG. 1 is an isometric view of a first embodiment of a disposable face shield showing our new design;

FIG. 2 is a side isometric view thereof shown in a used condition with a human head shown in broken lines;

FIG. 3 is a top plan view thereof;

FIG. 4 is a front elevation view thereof;

FIG. 5 is a rear elevation view thereof;

FIG. 6 is an enlarged portion view taken along line 6-6 of FIG. 4;

FIG. 7 is an isometric view of a second embodiment of a disposable face shield showing our new design;

FIG. 8 is a side isometric view thereof shown in a used condition with a human head shown in broken lines;

FIG. 9 is a top plan view thereof;

FIG. 10 is a front elevation view thereof;

FIG. 11 is a rear elevation view thereof; and,

FIG. 12 is an enlarged portion view taken along line 12-12 of FIG. 10.

The broken lines shown in the drawings form no part of the claimed design.

All surfaces not shown form no part of the claimed design.
